(57) **CLAIM**

The ornamental design for a computer display system or portion thereof showing a graphical user interface as shown and described.

DESCRIPTION

The FIGURE is a front view of a computer display system or portion thereof showing a graphical user interface showing the claimed design.

The peripheral broken lines in the FIGURE show the computer display system or portion thereof, and form no part of the claimed design.

The other broken lines in the FIGURE show a three dimensional environment within a field of view of the user, and portions of the graphical user interface, including the broken line text in the FIGURE, that form no part of the claimed design.
